(57) **CLAIM**

The ornamental design for a pipe seal scraper tool, as shown and described.

DESCRIPTION

FIG. 1 is a front perspective view of a pipe seal scraper tool according to the present application.

FIG. 2 is a front view of the pipe seal scraper tool of FIG. 1.

FIG. 3 is a rear view of the pipe seal scraper tool of FIG. 1.

FIG. 4 is a right view of the pipe seal scraper tool of FIG. 1.

FIG. 5 is a left view of the pipe seal scraper tool of FIG. 1.

FIG. 6 is a top view of the pipe seal scraper tool of FIG. 1; and,

FIG. 7 is a bottom view of the pipe seal scraper tool of FIG. 1.

The broken lines are included for the purpose of illustrating environmental structure and form no part of the claimed design.
